FISH HOLDING FORK

Claude Canion, 91 Tidwell Road,
Houston, Tex. 77022

Original design application Mar. 31, 1965, Ser. No. 84,529,
now Patent No. 205,884, dated Oct. 4, 1966. Divided
and this application Feb. 17, 1966, Ser. No. 1,879

Term of patent 14 years

(Cl. D44—29)

FIG. 1

FIG. 2

FIG. 3

FIG. 1 is an isometric view showing one side and a top view of a fish holding fork, showing my new design;

FIG. 2 is a side elevational view showing the other side thereof; and

FIG. 3 is a plan view showing the bottom thereof.

This application is a division of D. 84,529, filed Mar. 31, 1965, now Patent No. D. 205,884, granted Oct. 4, 1966.

I claim:

The ornamental design for a fish holding fork, as shown.
